UNITED STATES PATENT OFFICE.

JOHN H. PETTIT, OF GREAT FALLS, MONTANA.

AUTO-SPRING OILER.

1,395,518.

Specification of Letters Patent. Patented Nov. 1, 1921.

Application filed August 26, 1920. Serial No. 406,222.

To all whom it may concern:

Be it known that I, JOHN H. PETTIT, citizen of the United States, residing at Great Falls, in the county of Cascade and State of Montana, have invented certain new and useful Improvements in Auto-Spring Oilers, of which the following is a specification, reference being had therein to the accompanying drawings.

10 This invention relates to an auto spring oiler, and has for its object the construction of a simple and efficient oiling or lubricating device for automobile springs, that can be quickly attached or detached at the will of 15 the operator.

With this and other objects in view, my invention comprises certain novel combinations, constructions and arrangements of parts as will be hereinafter described, illustrated in the accompanying drawings, and more particularly pointed out in the appended claims.

In the drawings:

Figure 1 is a perspective view of a device 25 constructed in accordance with the present invention, shown attached to a spring, while—

Fig. 2 is a sectional view taken on line 2—2, Fig. 1, and looking in the direction of 30 the arrows.

Fig. 3 is a sectional view of another embodiment of the present invention, while

Fig. 4 is a perspective view of the same.

Fig. 5 is a fragmentary, perspective view 35 of an end of another embodiment of the spring clamps of the device.

Referring to the drawings by numerals, 1 designates the spring of the usual laminated structure. My spring oiler device 40 comprises a pair of inverted, substantially U-shaped spring clamps 2, and attached at 3, to the ends of these clamps, are plates 4. Each plate 4 is provided with inwardly-extending, horizontal prongs 5 upon their 45 upper and lower edges, which prongs hold the flat wick 6 from being displaced off the side of the spring 1 after the device has been placed upon said spring. Attached to the outer face of each plate 4 is a reservoir 50 or tank 7, containing the lubricant. Through aperture 8 of each plate 4, extends an auxiliary wick 9, which wick 9 is connected to the flat wick 6, so that the oil in the tank 7 will readily pass to the flat wick 6, thence 55 be distributed between the layers of the spring 1.

In the embodiment shown in Figs. 3 and 4, only one plate 4 is used, and upon corresponding ends of the springs 2, at 10, are attached a double prong device 11, the 60 prongs of which device extend inwardly and are adapted to be positioned between portions of the layers constituting the spring 1, see Fig. 3, whereby the device is held securely upon the spring 1 against accidental 65 displacement.

In the embodiment shown in Fig. 5, the prongs, instead of being formed upon the prong device 11, are integral with the spring 70 clamp 2.

While I have described the preferred embodiments of my invention, and have illustrated the same in the accompanying drawings, certain minor changes or alterations 75 may appear to one skilled in the art to which this invention relates, during the extensive manufacture of the same and I, therefore, reserve the right to make such alterations or changes as shall fairly fall within the scope of the appended claims.

What I claim is:

1. In a device of the class described, the combination of an elongated plate provided with a series of inwardly-extending prongs on its longitudinal edges, a tank attached to said plate, a wick on said plate between and secured by said prongs, an auxiliary wick extending through said plate into said tank and in communication with said first-mentioned wick, and a pair of bowed spring 85 clamps attached directly to the outside of said plate for holding the plate upon a spring.

2. In a device of the class described, the combination of a plate provided upon its 95 upper and lower edges with a series of inwardly-extending horizontal prongs, a flat wick against said plate between and secured by said prongs, a tank against said plate on the opposite side to said wick, said plate provided with an aperture opening into said tank, an auxiliary wick extending through said aperture and connected to said first-mentioned wick, and substantially U-shaped 100 spring clamps secured to the outside of said plate between its edges for holding the same upon a spring.

3. In a device of the class described, the combination of a plate, a tank and a wick in communication with said tank carried by 110 said plate, a spring clamp fastened to the outside of said plate, a prong device carried

by one end of said clamp and provided with a plurality of prongs, and the prongs of said prong device adapted to be positioned between portions of a spring for preventing 5 accidental displacement of the device off the spring.

4. In a device of the class described, the combination with a spring, of a wick and a tank against one side of said spring, a

prong device against the opposite side of 10 said spring, and a clamp straddling said spring and having one end fastened directly to said prong device and its other end fastened to and supporting said wick and tank against the spring.

In testimony whereof I hereunto affix my signature.

JOHN H. PETTIT.
